UNITED STATES PATENT OFFICE.

CECILIA R. BARNEY, OF PALO ALTO, CALIFORNIA.

DESIGN FOR A DOLL.

Application filed October 8, 1923. Serial No. 7,422. Term of patent 3½ years.

To all whom it may concern:

Be it known that I, CECILIA R. BARNEY, a citizen of the United States, residing at 214 Emerson Street, Palo Alto, in the county of Santa Clara and State of California, have invented a new, original, and ornamental Design for Dolls, of which the following is a specification, reference being had to the accompanying drawing, forming part thereof.

Fig. 1 is a front elevation of a doll showing my new design.

Fig. 2 is a side elevation thereof.

I claim:

The ornamental design for a doll, as shown.

CECILIA R. BARNEY.
